UNITED STATES PATENT OFFICE.

WILLIAM W. BOLLS, OF WASHINGTON, DISTRICT OF COLUMBIA.

PULP-CANAL FILE.

1,353,019,

Specification of Letters Patent. Patented Sept. 14, 1920.

Application filed December 23, 1919. Serial No. 346,910.

To all whom it may concern:

Be it known that I, WILLIAM W. BOLLS, a citizen of the United States, residing at Washington, in the District of Columbia, 5 have invented certain new and useful Improvements in Pulp-Canal Files, of which the following is a specification.

This invention relates to pulp canal files and the primary object thereof is to provide 10 a file for use in the opening and cleaning of canals and the like which has a positive and effective abrasive or cutting action both during longitudinal reciprocation as well as transverse rotation of the file whereby to expedite removal of the pulp as well as to more 15 effectively cleanse the canal.

A further object of the invention is to provide a file of this type which is formed with a multitude of individual cutting teeth 20 all of which are of varying formations whereby to provide a correspondingly different number of characters of cuts in operation with the end in view of quick and complete removal of all foreign matter and 25 shaping and enlarging of the canal for filling.

Further and other objects will later appear and be of themselves manifested in the course of the following description.

30 In the drawings:

Figure 1, is an elevation of the invention:

Fig. 2, is a fragmentary enlarged elevation of the file proper: and

Fig. 3, is a section on line 3—3 of Fig. 2.

35 In proceeding in accordance with the present invention, a handle 1 is employed to which the file 2 is suitably and rigidly affixed in any desired or preferred manner.

The file 2 is preferably formed of cold 40 drawn tempered wire, for which purpose piano wire has by experiment been found suitable and may be used accordingly. The file has a generally tapered conformation and upon its surface has formed a multitude 45 of teeth 3 which are provided by swaging *i. e.* displacing or mashing portions of the metal. The teeth 3 are all of varying types or characters and provide a cutting surface which is jagged and devoid of any regularity of formation. Thus some teeth are longer than others, some wider than others; 50 some truly rectangular; some curved; some

straight, and some of varying irregular shapes. In addition, the teeth are disposed in varying relations to the longitudinal axis of the file; for example, some aline with such axis; some traverse same at varying inclinations and some are curved relative to the axis. Moreover, some teeth are more abrupt than others and some project beyond the file surface to a greater degree or extent than others. The object aimed at is to assure an effective and clean cut of the instrument regardless of whether same is reciprocated longitudinally or transversely or continuously rotated.

The term scrapers as used contemplates any formation of the elements 3 which will cut, break down or have an abrasive action on the hard walls of the canal so as to enlarge, shape and prepare the canal walls for filling. Accordingly the elements 3, must be stout and not subject to bending in any direction when the file is rotated or reciprocated. The scrapers must cut into the hard walls of the canal and by disintegration of the walls effect enlarging thereof.

In actual practice, the instrument has been found to be of marked advantage and to afford removal of the walls of the pulp 80 canal in a more expeditious, certain and effective manner than with use of broaches and the like heretofore employed for the purpose.

The aforementioned irregular formation 85 and disposition of the cutting teeth also provides a file of greater longevity, since the teeth by being variously formed and related are not subjected to like wear in use of the instrument. In other words, the result of wear will affect the various teeth differently, so that all will not wear uniformly.

The mode of manufacture of the file results in a somewhat irregularly defined spiral formation of certain teeth as Fig. 2 95 suggests, though this is not essential to the success of the invention.

What is claimed is:

1. A pulp canal file for shaping, enlarging and cleaning the canal scrapers, which 100 are relatively short and closely related and said scrapers being of different formations and having their cutting edges variously arranged in irregular relation and at varying

angles to the longitudinal axis of the file and adapted to cut both during longitudinal reciprocation as well as transverse rotation of the file.

5 2. The method of making dental pulp canal files which consists in swaging a series of closely related and relatively short

scrapers upon the surface of a piece of tapered wire with the scrapers variously arranged in irregular relation and at varying 10 angles to the longitudinal axis of the wire.

In testimony whereof I affix my signature.

WILLIAM W. BOLLS.

It is hereby certified that in Letters Patent No. 1,353,019, granted September 14, 1920, upon the application of William W. Bolls, of Washington, District of Columbia, for an improvement in "Pulp-Canal Files," an error appears in the printed specification requiring correction as follows: Page 1, line 100, claim 1, after the word "canal" insert the words *having a multitude of*; and that the said Letters Patent should be read with this correction therein that the same may conform to the record of the case in the Patent Office.

Signed and sealed this 19th day of October, A. D., 1920.

[SEAL.]

M. H. COULSTON,

Acting Commissioner of Patents.
